ILLUSION APPARATUS

Filed Dec. 5, 1927

UNITED STATES PATENT OFFICE

ELMER E. SCHLOTZ, OF DENVER, COLORADO

ILLUSION APPARATUS

Application filed December 5, 1927. Serial No. 237,858.

This invention relates to apparatus for the production of stage illusions and its main object is to provide a simple contrivance adapted to mystify and entertain an audience in a theatre by making it appear that the performers move and act in a body of water. The invention is more particularly designed for use in musical acts inasmuch as it provides for the propagation of the sound 10 of music to the audience notwithstanding the body of water by which the musicians are separated from the audience.

An embodiment of the invention has been illustrated in the accompanying drawings in 15 which like characters of reference designate corresponding parts throughout the views and in which

Figure 1 represents a perspective view of the illusion apparatus in its preferred form, 20 Figure 2, a fragmentary section along the line 2—2, Figure 1,

Figure 3, a similar section showing a modified construction of the tank included in the apparatus,

25 Figure 4, a transverse section taken on the line 4—4 Figure 2, and drawn to a larger scale, and

Figure 5, a section similar to Figure 4, showing another modification in the construction of the tank.

The principal element in the invention is a tank 5 adapted to contain a body of water 6 and sufficiently large to form a screen between one or more musicians and their instruments on a stage, and an audience facing the stage. The tank which preferably is oblong in form, has in its rear side a cave-like recess 7 to provide a chamber for the actors or musicians as best illustrated in Figure 4, and the forward wall of this chamber is curved as shown at 8 for the two-fold purpose of serving as a sounding board and of preventing any break in the vista through the tank from the location of the audience.

45 The ends 9 of the tank may be screened from view by curtains 10 and the illusion may be enhanced by a back-drop 12 upon which a marine scene is depicted. The drop curtain is spaced from the tank to provide a

passage 13 for the sound of the music made by the performers in the chamber 7.

In order to still further enhance the illusion, motion may be imparted to the water in the tank by means of a fan 14 or other suitable agitating device, and the water may contain live fishes or shown at 15, or plants, shells and other animals or objects found in nature below the surface of the ocean.

The drawings illustrate different methods of constructing the tank, it being apparent that if the apparatus is used as one of a number of stage acts, as in vaudeville, it is desirable that it be readily moved onto the stage and removed after the act is finished.

55 Figures 1 and 2 show the tank in its simplest form. The ends 9 and the bottom 16 of the structure can be made of wood, metal or other material while the front 17 and the back 18 are composed of panes of glass. The 60 panes are set in frame 19 provided with packing strips of rubber or other suitable material to prevent leakage and the various parts are forced into water-tight contact by set screws 20 in the end walls 9.

65 In Figure 3 is shown a tank composed of sections 21 which are placed in end-to-end engagement. The sections can be made entirely of glass or the bottom may be made of wood or metal. This form of the invention has the advantage of being easily moved from one place to another as is desirable in stage acts, particularly if the tank is large.

70 The tank 22 illustrated in Figure 5 has both its front wall and its rear wall curved in substantially parallel relation to each other. A tank of this character, especially if made in sections, is easily transported which, obviously, is of great advantage to actors travelling from one city to another as 75 in a vaudeville circuit.

75 A narrow tank also contains less water and is more readily filled and emptied.

80 In short, the tank may be made of any form best suited for the particular act in 85 which it is used and it is to be understood that different variations in the form of the tank and also in the construction of the same may be resorted to within the scope of the invention.

In the use of the illusion apparatus as shown in the drawings and hereinbefore described, the audience sees the body of water and through the same the actors which may enter the chamber or space behind the tank 5 while the stage is dark or by means of a slide or other contrivance, which not being an essential part of the invention, have not been shown in the drawings.

10 The illusion is heightened by dressing the actors in appropriate costumes to represent fishes or divers or mermaids and by the use of properly directed lamps, the entire scene may be illuminated so as to enhance its artistic and mystifying effect upon the audience.

15 If the tank is sufficiently large, the chamber or space behind the same may contain a piano and other instruments and a number of musicians may be gathered in the chamber to produce orchestral or choral music. The sound of the music is propagated to the audience through the space 13 and can be clearly heard which, of course, increases the delusion.

20 25 While the above described invention is more particularly designed for stage illusion, it may be adapted for house use as a tank for goldfish etc. In this case, the chamber, which in the illusion apparatus is occupied by the performers, can contain plants which would show through the front of the tank, and thereby create the effect that they are growing under water.

30 35 Having thus described my invention, what I claim and desire to secure by Letters Patent is:—

1. In illusion apparatus, a tank containing a body of water and adapted to form a liquid screen before an audience in a place of entertainment, the rear wall of the tank curving inwardly to provide a chamber for performers.

40 45 2. In illusion apparatus, a tank containing a body of water and adapted to form a liquid screen before an audience in a place of entertainment, the front and rear walls of the tank being curved over a space to provide a chamber for performers behind the tank.

50 55 3. In illusion apparatus, a tank containing a body of water and adapted to form a liquid screen before an audience in a place of entertainment, the rear wall of the tank extending inwardly to provide a chamber for performers.

In testimony whereof I have affixed my signature.

ELMER E. SCHLOTZ.
